CLAIM

I claim the ornamental design for a pipe for fire fighting/ extinguishing, as shown.

DESCRIPTION

FIG. 1 is a side perspective view of the pipe for fire fighting/ extinguishing from the top;

FIG. 2 is a side perspective view of the pipe for fire fighting/ extinguishing from the bottom;

FIG. 3 is a side view of the pipe for fire fighting/extinguishing;

FIG. 4 is another side view of the pipe for fire fighter/extinguishing;

FIG. 5 is an opposite side view of the pipe for fire fighter/ extinguishing shown in FIG. 3;

FIG. 6 is an opposite side view of the pipe for fire fighter/ extinguishing shown in FIG. 4;

FIG. 7 is a top view of the pipe for fire fighting/extinguishing;

FIG. 8 is a bottom view of the pipe for fire fighting/extinguishing;

FIG. 9 is a side perspective view from the top of a 2nd embodiment of the pipe for fire fighter/extinguishing shown in FIG. 1;

FIG. 10 is another side perspective view from the bottom of the pipe for fire fighter/extinguishing shown in FIG. 9;

FIG. 11 is a side view of the pipe for fire fighter/extinguishing shown in FIG. 9;

FIG. 12 is another side view of the pipe for fire fighter/ extinguishing;

FIG. 13 is an opposite side view of the pipe for fire fighter/ extinguishing shown in FIG. 11; and,

FIG. 14 is an opposite side view of the pipe for fire fighter/ extinguishing shown in FIG. 12.
